UNITED STATES PATENT OFFICE

TREADWAY B. MUNROE, OF CHICAGO, ILLINOIS, ASSIGNOR, BY MESNE ASSIGNMENTS, TO THE CELOTEX COMPANY, OF CHICAGO, ILLINOIS, A CORPORATION OF DELAWARE

SPROCKET

Application filed June 21, 1926. Serial No. 117,644.

This invention relates to a sprocket, and more especially to that type adapted to be driven rather than to drive, and has for its object to provide a construction more efficient in use than those heretofore proposed.

With this and other objects in view, the invention consists in the novel details of construction and combinations of parts as will be more fully hereinafter disclosed and particularly pointed out in the claims.

Referring to the accompanying drawings, forming a part of this specification, in which like numerals designate like parts in all the views:

15 Fig. 1 illustrates a device adapted to be driven through the use of a type of sprocket heretofore employed;

Fig. 2 is a view similar to Fig. 1 showing the substitution of this invention for the heretofore employed sprocket;

Fig. 3 is an enlarged detail view similar to Fig. 2 and adapted to illustrate the operation of a sprocket made in accordance with this invention;

25 Fig. 4 is a greatly enlarged view of the improved sprocket; and

Fig. 5 is a sectional view taken on the line 5—5 of Fig. 4 and looking in the direction of the arrows.

30 In order that this invention may be the more clearly understood it is said that in my U. S. Letters Patent #1,501,966, dated July 22, 1924, there is disclosed a drying apparatus in which there is provided a great plurality of rollers adapted to support and move the material passing through the dryer. On one end of each of these rollers there is secured a sprocket which is adapted to be engaged by a driving chain so that said chain

35 will rotate, at uniform speed, the rollers carrying the material. However, greater difficulty was experienced in the use of this particular type of sprocket in that the driving chain rode up and over the end of the teeth of the sprocket without revolving the rollers,

with the result that the material was dragged over these non-rotating rollers, the friction therefrom working against the efficient delivery of the material from the dryer. Guide blocks or shoes had to be provided which were secured to the framing of the apparatus and which were adapted to overlie the driving chain at frequent intervals to keep said chain down in mesh with the sprocket teeth. However, this was found objectionable in that 50 said shoes and the chain became worn from their sliding contact causing expensive replacements. Considerable experimentation followed with different types of sprockets, etc., to overcome this deficiency, thus developing the sprocket forming the subject matter 55 of this application which has not only overcome the above objections, but has proved to be of value otherwise.

Referring to the drawings, there is disclosed in Fig. 1 one of a pair of side frame members, numbered 1, in which is suitably journaled the ends of the tubular rollers 2 adapted to convey the material 3 to be dried. On one end of each of the rollers is securely 60 fixed the sprocket 4 the teeth of which are adapted to be engaged by the driving chain 5 which receives its motion from a shaft 6 which in turn derives its power from a source 65 not shown through a main driving chain 7 and sprocket 8, all as will be clearly understood from said figure and with reference to my aforementioned patent. 9 designates any suitable type of adjustment by which the chain 5 may be kept substantially taut. 70 However, it will be observed that the pitch of the teeth of the sprocket 4 is the same as the link distance or pitch of the chain 5, and further, that each tooth has a face 10 which is substantially radially formed. The 75 result of this construction is that the pins or pintles of the chain 5 will ride upwardly and off said face 10 because the weight of said chain is insufficient to insure the same 80 meshing with each sprocket 4. The result 85 90

of this is that the chain 5 will pass over a great number of the sprockets 5 without engaging the same, thus leaving the rollers associated with the non-rotating sprockets 5 immovable.

In Figs. 2 and 3 substantially the same numerals have been used to designate similar and like parts, but in these figures it will be observed that the improved sprocket 15 has been employed, and that the face 16 of each tooth, corresponding to the face 10 of the teeth of the sprocket 4 illustrated in Fig. 1, is not radially disposed, but is outwardly and rearwardly inclined thus producing a hook-shaped tooth. Assuming the generally adopted definition of the pitch of the teeth of any sprocket as being the distance on the pitch line from the center of one tooth to the center of the next adjacent tooth, and further assuming that all the teeth are symmetrically formed with equal dimensions, then it will be obvious that the distance from any point on the pitch line associated with a tooth to a symmetrical point on said pitch line associated with the next adjacent tooth will be equal to the pitch distance of said sprocket. Therefore, with particular reference to Fig. 4, it will be observed that the dot and dash line 17 is representative of the pitch distance of the sprocket teeth inasmuch as said line is equal in length to the distance between the two small circles representing the centers of curvature of the pockets of two adjacent symmetrical teeth. In the following discussion, therefore, the line 17 is referred to as the pitch of the teeth of the sprocket 15, and from said Fig. 4 it will be observed that said pitch is less than the link distance or the pitch 18 of the chain. It will still further be observed that the end of each tooth 19 of this sprocket has been angularly cut off to provide an arcuately chamfered surface 20 so that there will be provided a space 21 between said chamfer 20 and the outer circumference of the pintle 22 of the chain 5 when said chain passes over said sprocket.

In Fig. 4 there is clearly shown the formation of each tooth 19 of the sprocket and from said figure it will be seen that the surface 16 of each tooth is flat, as is also the opposite face 23, but that the latter face is longer than the former, and disposed at such a wide angle to the radius of the sprocket as will give to the tooth maximum bracing strength against the thrust of the chain 5. That is to say, said surface 16 constitutes the working surface of the tooth and lies in a plane 24 tangent to a circle 25 as at the point 26 which is to one side of the center 27 of the sprocket. Stated in still other language, a radial line 28 drawn from the center 27 of the sprocket through an apex 29 of any tooth will intersect the plane 24 passing through the face 16 of that tooth. Thus it will be

seen, that when the sprocket 15 is rotating in the direction indicated by the arrow, the face 16 of each tooth will be outwardly and rearwardly inclined to form a pocket 30 having a rounded bottom adapted to receive and seat the pintles of the links of the chain 5.

By such a construction it will be obvious that when the chain 5 is moved in the direction of the arrows indicated in Fig. 2, the particular pintle 32, moving in the direction of the arrow, will have become seated in the pocket therefor, with the result that said pintle will bear against the surface 16 of the tooth 33 and cause the same to rotate the sprocket in the direction indicated. The chain 5 being under continual motion, will move the sprocket and cause the next following tooth 34 to move upwardly and around toward the left as seen in Fig. 4. But due to its pitch distance from its preceding tooth 33, and also due to its novel and peculiar shape, the apex of tooth 34 will easily pass into the space between the pintles 32 and 36 with the result that, as said chain continues to move to the left, the pintle 32 will cause the rotation of the sprocket to continue until said pintle has passed the position illustrated in Fig. 4 before it will have a tendency to ride up the surface 16 of the tooth 33. This will be perfectly obvious, but may be stated as caused by the fact that in the position illustrated in Fig. 4 the surface 16 of the tooth 33 is in a substantially vertical plane, and therefore the pintle 32 will not move over said surface until the surface has assumed an angular position further to the left as seen in said figure. But when the surface 16 of the tooth 33 has reached that particular angular position at which the pintle 32 will tend to move upwardly thereover, the next following tooth 34 of the sprocket will have moved upwardly and to the left so that the chamfered surface 20 of the end of said tooth will lie above the horizontal center of the following pintle 36 of the chain 5. Continued movement to the left of the chain 5, will cause the circumference 22 of the pintle 36 to contact with the chamfered surface 20 of said tooth 34 when the preceding pintle 32 begins to leave its pocket 30, with the result that said chamfered surface will be struck by the following pintle 36 (as clearly illustrated in dotted lines in Fig. 3) and deflected downwardly therefrom, thus insuring the seating of said pintle 36 in the pocket behind said tooth 34, and causing the continued rotation of the sprocket 15 by pressing against said tooth. Thus it will be seen that each link of the chain is forced downwardly into engagement with the sprocket 15, or in other words, prevented from "jumping" off of said sprocket. The momentary pause in the rotation of the sprocket 15, due to the difference in pitch dimensions of the sprocket and its chain, is

practically negligible in so far as the movement of the material to be delivered in the apparatus is concerned.

In Fig. 5 is shown a sectional view of the sprocket 15 and in which is particularly illustrated the hub portion 40 extending to either side of the plane of the teeth 19 to form a relatively wide bearing surface 41 with the outer circumference of the hub of the tubular 10 drying rolls 2. The sprocket 15 is adapted to be secured to the rolls by any suitable means, such as the usual set screws not shown but operating in the threaded bores 42 with which the hub 40 of the sprocket is provided, 15 said bores being on opposite sides of the plane of the teeth 19.

From the foregoing, it will therefore be seen that there is provided a sprocket adapted to be driven by a tangential chain which 20 is provided with means to retain said chain and sprocket in engagement. In other words, this particular sprocket is not adapted at all for use with chains which wrap around 25 said sprocket to any appreciable extent, because the pitch of the teeth of the sprocket is less than the pitch of the chain and therefore the chain would not fit the sprocket if wrapped thereabout. Further, no matter 30 how much resistance is offered to the chain through said sprocket, the chain will always hug the sprocket, or in other words, the more resistance offered by the sprocket to the chain the tighter will the chain cling to the sprocket.

35 Also it will be observed that this tangentially driven sprocket comprises means to prevent an outward thrust on the chain sufficient to allow said chain to become disengaged from the sprocket, said means comprising 40 the plurality of non-radial or hook-shaped teeth 19 which are outwardly and backwardly inclined with relation to the direction of rotation of the sprocket, and a pocket 30 associated and coacting with the 45 working face 16 of each tooth.

Lastly, it will be seen that this sprocket has a pocket formed at the base of the working face only of each tooth which is adapted to receive and hold against radial displacement 50 a pintle such as 32 of the chain due to the outwardly and backwardly inclination of the teeth of the sprocket and the working face associated therewith. Further, each 55 tooth of the sprocket has a means disposed at the end thereof and comprising the arcuate surface 20 which is adapted to direct a pintle of the chain into the pocket 30 associated with said tooth as the preceding pintle leaves 60 its pocket.

It is obvious that those skilled in the art may vary the details of construction as well as the arrangements of parts without departing from the spirit of the invention, 65 therefore it is not desired to be limited to

the foregoing disclosure except as may be demanded by the claims.

What is claimed is:

1. In a sprocket the combination of a plurality of teeth whose pitch is less than the pitch of the chain coacting therewith said teeth having a working face outwardly and backwardly inclined; a pocket formed by each tooth adapted to receive and hold a pintle of said chain; and means adapted to direct said pintle into said pocket. 70

2. In a sprocket the combination of a plurality of teeth whose pitch is less than the pitch of the chain coacting therewith; a pocket formed by each tooth adapted to receive and hold a pintle of said chain; and means adapted to direct said pintle into said 80 pocket as the preceding pintle leaves its pocket.

3. In a sprocket the combination of a plurality of teeth whose pitch is less than the pitch of the chain coacting therewith; a pocket formed by each tooth adapted to receive and hold a pintle of said chain; and means disposed at the end of each tooth 85 adapted to direct said pintle into said pocket. 90

4. In a sprocket the combination of a plurality of teeth whose pitch is less than the pitch of the chain coacting therewith; a pocket formed by each tooth adapted to receive and hold a pintle of said chain; and means comprising the arcuate end of each tooth adapted to direct said pintle into said 95 pocket.

5. In a sprocket adapted to be driven by a chain, means including a plurality of hook-shaped teeth to prevent an outward thrust on said chain disengaging the same from the sprocket when the chain is in tangential relation thereto, said teeth having a pitch less than the pitch of the chain coacting therewith as well as a flat working face for the 100 pintles of said chain.

6. In a sprocket adapted to be driven by a chain, means including a plurality of non-radial teeth to prevent an outward thrust on said chain disengaging the same from the sprocket when the chain is in tangential relation thereto, said teeth having a pitch less than the pitch of the chain coacting therewith as well as a flat working face for the 105 pintles of said chain. 110

7. In a sprocket adapted to be driven by a chain, means including a plurality of outwardly and backwardly inclined teeth to prevent an outward thrust on said chain disengaging the same from the sprocket when the chain is in tangential relation thereto, said teeth having a pitch less than the pitch of the chain coacting therewith as well as a flat working face for the 115 pintles of said chain. 120

8. In a sprocket adapted to be driven by a chain, means including a plurality of non-radial teeth and a pocket associated with each 125

to prevent an outward thrust on said chain disengaging the same from the sprocket when the chain is in tangential relation thereto; said teeth having a pitch less than 5 the pitch of the chain coacting therewith as well as a flat working face for the pintles of said chain.

9. In a sprocket adapted to be driven by a chain, means including a plurality of non-10 radial teeth having a flat working face and a pocket coacting with the working face of each to prevent an outward thrust on said chain disengaging the same from the sprocket when the chain is in tangential relation 15 thereto, said teeth having a pitch less than the pitch of the chain coacting therewith.

10. In a sprocket adapted to be driven by a chain, means comprising a plurality of non-20 radial teeth each provided with a bevelled end, and a pocket coacting with the working face and said bevel end of each tooth to prevent an outward thrust on said chain disengaging the same from the sprocket when the chain is in tangential relation thereto.

25 11. The combination with a chain of a sprocket provided with means to increase the pressure therebetween upon increasing the driving resistance of the sprocket when said chain is in tangential relation thereto, said 30 means adapted to provide a positive and free engagement and disengagement of said chain.

12. The combination with a chain of a sprocket having teeth whose pitch is less than 35 the pitch of the chain, each tooth being provided with means to direct the pintles of said chain into a pocket associated with each tooth.

40 13. The combination with a chain of a sprocket having teeth whose pitch is less than the pitch of the chain, each tooth being provided with means comprising a rearwardly bevelled end portion to direct the pintles of said chain into a pocket associated with 45 each tooth and adjacent said bevelled end.

14. The combination with a chain of a sprocket having a plurality of teeth whose pitch is less than the pitch of said chain; a 50 pocket formed by each tooth adapted to receive and hold a pintle of said chain; and means adapted to direct said pintle into said pocket.

15. The combination with a chain of a sprocket having a plurality of teeth whose 55 pitch is less than the pitch of said chain; a pocket formed by the working face of each tooth adapted to receive and hold a pintle of said chain; and means adapted to direct said pintle into said pocket.

60 16. The combination with a chain of a sprocket having a plurality of teeth whose pitch is less than the pitch of said chain; a 65 pocket formed by the working face of each tooth adapted to receive and hold against radial displacement a pintle of said chain;

and means associated with said pocket and working face adapted to direct said pintle into said pocket.

17. The combination with a chain of a sprocket having a plurality of non-radial 70 teeth whose pitch is less than the pitch of said chain; a pocket formed by each tooth adapted to receive and hold a pintle of said chain; and means at the end of each tooth adapted to direct said pintle into said pocket. 75

In testimony whereof I affix my signature.

TREADWAY B. MUNROE.
